DESIGN FOR A TEXTILE FABRIC

Lillian Goodman, Brooklyn, N. Y., assignor to Mitchell Brothers, Inc., New York, N. Y., a corporation of New York

Application July 7, 1939, Serial No. 85,879

Term of patent 3½ years

To all whom it may concern:

Be it known that I, Lillian Goodman, a citizen of Lithuania, residing at Brooklyn, in the county of Kings, city and State of New York, have invented a new, original, and ornamental Design for a Textile Fabric, of which the following is a specification, reference being had to the accompanying drawing, forming part thereof.

The drawing shows a plan view of a textile fabric illustrating my design, a complete unit of said design being embraced by the intersecting section lines, said unit being repeated longitudinally and transversely throughout the entire length and width of the fabric.

I claim:

The ornamental design for a textile fabric, as shown and described.

LILLIAN GOODMAN.
